UNITED STATES PATENT OFFICE.

OTTO KIRSCH, OF BROOKLYN, NEW YORK.

TAPE-FRAME AND FEEDER-FRONT FOR PRINTING-PRESSES.

1,264,305.

Specification of Letters Patent. Patented Apr. 30, 1918.

Application filed July 5, 1917. Serial No. 178,552.

To all whom it may concern:

Be it known that I, OTTO KIRSCH, a citizen of the United States, residing in the borough of Brooklyn, city of New York, county of Kings, and State of New York, have invented new and useful Improvements in Tape-Frames and Feeder-Fronts for Printing-Presses, of which the following is a specification.

- 10 The invention comprises certain improvements in sheet feeders for printing presses, the same relating more especially to a tape-frame and feeder front, and to front and side registering means upon the feeder front.
- 15 A particular object is to improve the construction and operation of such devices and their manner of coördination. A further object is so to construct and organize the parts as to permit the forwardly projecting 20 structure to be positioned over the regular feed table of the press. These ends are attained by the features of construction and relation hereinafter described, reference being had to the accompanying drawings 25 illustrating the preferred embodiment of the mechanism.

Figure 1 is a side elevation of the apparatus in operative relation to a press, the gripper cylinder, front stops and feed table of 30 which are indicated in broken lines;

Fig. 2 is a plan view;

Fig. 3 is a vertical longitudinal section through the feeder front showing one of the front registering devices in its rear or 35 receiving position, broken lines being used to indicate the corresponding position of the pressure arm of the side registering device;

Fig. 4 is a view like Fig. 3 showing the front registering device in an advanced position, and indicating by broken lines the pressure arm and roller of the side registering device approaching the sheet;

Fig. 5 shows the most advanced position, with the front registering blade and its 45 pressure member raised off the sheet, and the pressure roll of the side registering device bearing upon the sheet;

Fig. 6 is a rear elevation of one of the front registering devices;

50 Fig. 7 is a view partly in side elevation and partly in vertical section of the pressure means of the side registering device;

Fig. 8 is a rear view thereof;

55 Fig. 9 is a fragmentary front elevation of the operating mechanism, with parts broken away and in section;

Fig. 10 is an enlarged front elevatiton of a portion of the side registering slide and its immediate operating connection; and

Fig. 11 is a sectional side elevation of an 60 operating element.

A frame 2, which may be termed the magazine frame, is constructed to stand upon the floor and holds the stack of sheets 3 upon a suitable rising table or platform 4. 65 Pneumatic mechanism 5 in this frame above the front of the stack advances the sheets successively from the stack. For a fuller understanding of these parts of the feeder reference may be had to Patent 1,105,352 of 70 July 28, 1914, and copending applications, Serial Nos. 178,626 and 178,627, filed July 5, 1917.

The sheets fed from the stack are deposited upon endless traveling tapes 6, by 75 which they are carried forward at a descending inclination to registering devices mounted on the feeder front 7. The said tapes pass around a roller 8 in the frame 2 and another roller 9 in the forward portion of 80 a flat sloping tape-frame 10. This tape-frame comprises side bars 11 connected by suitable structural cross members, and carrying at their forward ends a table member constituting the feeder front 7. Arms 12 85 are pivoted upon a transverse rod 13 extending between the side bars 11 toward the rear and bear rollers 14 resting upon the lower courses of the tapes, to take up slack therein. The rear ends of the bars 11 are pivotally connected to the frame 2 at 15, so that the whole forwardly projecting structure can be swung up or down. By virtue of 90 this mounting and the dispositions whereby the under side of the tape-frame and feeder 95 front are left unobstructed, the feeder can be applied to a press by merely moving its frame 2 up to the regular feed table 16 and letting down the frame 10 like a draw-bridge to span the space between the mechanism 5 and the gripper cylinder 17 of the press. In this position the tape-frame is 100 supported partly upon the feed table beneath, for which purpose its side bars may be provided with feet 18.

Front registering devices 20 coöperate with the feed surface of the table member 7 and with extensions thereof formed by forward projections 21, which overlie the gripper cylinder 17 and extend slightly beyond 110 the front stops 22.

The said projections have rearward ex-

tensions 23 which pass beneath said table member, and the shoulder 24 at the junction of said rearward extensions and the projecting portions is undercut to engage over 5 a bevel 25 formed on the edge of the table. Both the front registering devices and the 10 projections are laterally shiftable; and to hold the projections in any selected positions there is a transverse clamp bar 26, which passes substantially all the way across 15 beneath the table member, and under the extensions 23, which it is formed to engage. A longitudinal groove 27 in the upper face of the clamp bar receives a down-turned lug 28 on the end of each extension, so as to prevent all possibility of forward displacement of the projections.

The clamp bar 26 is clamped in its turn by two-armed clamp levers 29 disposed longitudinally and lying close to the under side of the table member 7. The said levers are fulcrumed upon pivots 30 near their forward ends and are acted upon at their rear ends by a rotatable transverse clamp 25 rod or cam member 31, having a handle 32 in projecting relation at one side of the feeder front. The said rod passes between the tails of the levers and the table member 7, and has cut-away portions 33 constituting low areas, which relieve the pressure on the clamps when the rod is turned to bring these portions over the levers. The forward portions of the levers have recesses 34 formed to receive the clamp bar and to 30 hold the same in a fixed position lengthwise of the feeder. Owing to the interlocking engagement of the clamp levers, clamp bar, and the rear extensions 23, and the limited movement permitted to the levers by the 35 actuating and holding member 31, when the latter is moved to release the pressure, the parts are retained in assembled relation while unclamped and during the transverse shifting of the members 21.

40 The levers 29 are disposed alongside of fixed longitudinal pieces 35, from which the pivots 30 project. Said pieces are secured to the under side of the table member 7 by screws 36 passing into the portions of 45 the member at opposite sides of a transverse slot 37, which table portions are accordingly united by the longitudinal pieces.

A rock-shaft 38 extends transversely 50 across the feed front at a distance above the same, and is utilized as the immediate support and operating means for the front registering devices. The end portions of the rock-shaft are journaled in brackets 39 rising from the sides of the feeder frame; and 55 it is oscillated by means of a cam 40 on a transverse rotary shaft 40^a in the frame 2, a cam roll lever 41 pivoted at 42 to said frame and held to the cam by a spring 43, and a link 44 pivoted to said lever at one 60 end and at the other adjustably pivoted in a

slotted arm 45 carried by the rock-shaft. The driving connections are thus located in the frame 2, or at the side of the frame 11, or above the same, so that they do not encroach upon the space reserved for the 70 press feeder table 16.

Each of the front registering devices includes a rocker-arm 46 fixed to the rock-shaft 38 and extending downward into proximity to the front feed surface. 75 Pivoted to the lower end of this arm at 47 is another, forward extending, short arm or tip 48, which may have a rearward and upward extending tail 49, behind the arm 46. The members 46 and 48 constitute a pivotally-jointed, reciprocatory carrier for a flexible forwarding blade 50, of which the part 48 is the immediate holder. The said blade 50 consists of a length of flat spring, which normally lies longitudinally along 85 the feed surface, so as to bear frictionally with its flat under face upon the sheet 8, when the latter has been brought beneath it by the action of the tapes. The blades operate over the surface of the table portion 7 and its forward extensions 21, and the latter are formed with recesses wherein are mounted rollers 51, the tops of which constitute slightly raised movable portions of the surface. The rear ends of the blades 90 are secured in slots in the holders 48, and their forward ends are preferably free. These ends being in advance of the sheet as long as they are close to the feed surface and being lifted while the sheets are carried 100 forward by the gripper cylinder, have no opportunity to engage or injure the paper, but it is obvious that they may be slightly turned up if desired.

Each front registering device includes 105 means for pressing the flexible blades against the feed surface at a point forward of the holders. Such means preferably includes, for each device, an arm 52 pivotally hung upon the rock-shaft 38 or a bearing 110 encircling the same, said arm extending forward and downward in front of the blade carrier and terminating in a pressure roller 53 normally resting upon the blade 50 directly above the roller 51. Each arm 52 115 is desirably composed of a pair of members at opposite sides of the arm 46, being connected by the axle of the roller 53 and by a piece 54, through which is threaded an adjustable abutment screw 55, the rear end of which is in position to be encountered by the arm 46 after the latter has executed the major portion of its forward movement. The pressure roller is loaded by weights 56 placed upon a rod 57 rising from the arm 120 52. By removing a nut 58 weights may be added or removed, to vary the pressure in accordance with the characteristics of the paper being fed.

The arm 46 of each front registering de- 130

vice normally extends downward and rearward and its forward movement carries it substantially to a vertical position. The holder 48, as heretofore indicated, is capable of limited pivotal movement upon the carrier arm. The limits of this relative movement are determined by coacting abutments upon the two jointed portions, and the precise limits selected having an important effect upon the action of the blade upon different grades, thicknesses and stiffness of paper, such abutments are made adjustable. The abutment which stops relative movement after a period of forward movement of the carrier comprises a screw 59 threaded through the tail 49 of the holder 48 and adapted to strike against the back of the arm 46. The stop which limits the reverse relative movement upon the backward movement of the carrier is a screw 60 extending downward and forward through the arm 46 to bear upon the top of the holder 48.

The operation of the front registering devices will now be described. When the sheet is brought to them by the tapes they are disposed and held in the position of Fig. 3. In this condition, each blade 50 having been drawn rearward against the resistance of the pressure means, its holder 48 is against the abutment 60 and the blade is inclined rearward and slightly upward from its forward point of contact with the roller 51, thus presenting a tapering, elongated throat into which the paper is introduced until stopped by the increasing contraction of the space. In this way the forward edge of the sheet is given a preliminary alining. The arms 46 now rock forward, carrying the fulerums 30 of the holders 48 with them. Owing to the resistance to the passage of the springs between the rollers 51, 53, this forward movement produces a relative angular movement between the members 46, 48 of each blade 45 carrier, until the tails 49, through their stops 59, contact with the arms 46. This relative movement has the effect of laying the blades substantially flat upon the paper for the majority of their length, closing the 50 tapering throats. The blades thus frictionally engaged with the paper and pressed thereagainst by the weighted pressure rollers 53, advance the sheet until its forward edge abuts against the front stops 22. The slight 55 remaining extent of forward movement then brings the carrier arms 46 against the abutment screws 55, and thereafter the pressure devices and the blades are raised slightly off the sheet, as seen in Fig. 5. Rearward 60 movement of the carrier, after the sheet has been engaged and carried away by the gripper cylinder, lowers the blades and the pressure members upon the feed surface again, and retracts the blades to the receiving position represented in Fig. 3.

The side registering means comes into action after the front registering means has completed its operation and cleared the paper, and its function is to shift the paper laterally against a side stop 61. The side stop may be of known character, comprising a disk laterally adjustable upon a base 62, which may be secured to the table member 7 at any position cross-wise of the latter, by bolts 62' engageable in holes 63 in 75 the table and passing through slots 64 in the base.

A transverse slide 65 is mounted in the slot 37 of the feeder front, and is advantageously formed of two flat strips of metal 80 united face to face, the upper strip occupying the slot and being sufficiently thick to rise slightly above the general plane of the feed surface, and the lower strip being wider than the slot so as to engage beneath the 85 table member at opposite sides thereof. The lower portion of the slide is supported in recesses 66 in the top of the longitudinal fixed members 35 which extend across the slot beneath the table. The top rear edge 90 of the slide and the top front edge of the slot are preferably beveled, as indicated, to prevent the paper catching thereon.

Reciprocation of the slide may be effected by a face cam 67 on the shaft 40^a, a cam 95 roll lever 68, a link 69 connecting said lever with an arm 70, the foregoing parts being located in the frame 2, a longitudinal rock-shaft 71 extending forward adjacent the side of the tape-frame 10 and bearing the 100 arm 70 at its rear end, and a gear segment 72 on the forward end of this shaft meshing with rack teeth 73 on the slide. These driving connections likewise leave the space beneath the frame 10 unobstructed; and to permit the transmission line to break when the frame is moved about its pivot a separable coupling 74 may be introduced therein. The face cam 67 bears laterally against a 105 collar 75 on the shaft 40^a, with which collar it may be reversibly engaged by pin and hole connections 76, so constructed and arranged that the cam can be moved outward on the shaft to disconnect it from the collar, displaced rotatively through an angle of 110 115 180° relatively thereto, and then reengaged. The spring 77 connected to the cam roll lever 68 serves to hold the cam against the collar so as to prevent disconnection while the mechanism is in operation. The purpose of shifting the cam will appear herein-after.

Coöperating with the slide is a pressure device 78 capable of movement to and from the slide, and advantageously mounted upon 125 the same rock-shaft 38 which supports and operates the front registering devices. The said pressure device comprises an arm 79 fixed to the shaft, and like the front registering devices capable of being shifted lon- 130

gitudinally thereon to occupy different positions transversely of the feeder front. The said arm projects rearward and carries another angled arm 80, the upper end of which 5 is pivoted to the primary arm at 81, while its lower end bears a pressure roller 82, the axis of rotation of which is at right angles to the axes of the pressure rollers 53 of the front registering devices. When the arm 79 10 is raised the arm 80 rests against a stop pin 83, and when it is lowered, a yielding pressure of the roller upon the sheet is produced through the agency of a spring 84 housed in a bore in the top of the arm 80 beneath 15 a plunger 85, which is contacted by the end of an adjusting screw 86 threaded through an overhanging portion of the arm 79.

A bracket 87 is screwed to the side of the arm 80, and includes a downward projecting portion 88 extending into proximity to the slide and a laterally projecting portion 89 at a distance thereover. To the lower end of the portion 88 is secured one end of a laterally projecting spring blade 90, the 20 body of which is downwardly offset to constitute a flexible pressure foot, extending toward and into proximity to the side stop 61 and passing beyond the side stop. A set-screw 91 threaded downward through the 25 laterally projecting part 89 constitutes an adjustable abutment to limit upward tilting of the blade about the offset shoulder 92 as a fulcrum when the pressure device is depressed into contact with the paper.

30 It will be understood that the side stop 61 is capable of being placed at any position transversely of the feeder front, and also of being reversed, so as to coöperate with either side edge of the paper. The pressure device 78 is also laterally shiftable on the shaft 38, and when the stop 61 is placed at the opposite side of the feeder, it may be removed from the shaft and replaced upon the remote portion adjacent the stop in its new 35 position. When this is done the bracket 87 may be removed from the arm 80 and applied to the opposite side thereof so that the presser foot blade will extend toward the stop. Obviously if desired one or more of 40 the pressure devices 78 may be mounted upon the rock-shaft, thus obviating the necessity of removing and replacing one of them when the guide is changed from left to right and vice-versa, and also enabling 45 the sheet to be driven laterally at a plurality of points, instead of at one point, if desired.

From Figs. 3, 4 and 5, it will be perceived 50 that the angular relation of the arms 46 and 79 of the front and side registering means upon the rock-shaft is such that when the front registering devices are in their rearward receiving positions with the blades 50 converging upon the feeding surface, the 55 arm 79 is raised at a substantial elevation,

so as to hold the pressure roller 82 well above the paper. As the front registering devices execute their forward movement, the pressure device of the side registering means is brought downward, but its roller 70 75 82 does not bear upon the paper until the blades 50 have finished advancing the sheet against the front stops and have, with their pressure means, been lifted off the sheet. Fig. 5 shows the front registering devices 75 thus lifted and the pressure roller 82 down upon the sheet directly over the slide 65. The cam 67 in its rotation now causes the slide 65 to move in the direction of the side stop, and by virtue of the coöperation of 80 the pressure means moves the side edge of the sheet against that stop. During this movement the front registering devices remain off the sheet. For the succeeding period one of two dwell portions 92, 93 on 85 the cam 67 holds the slide stationary. The movement of the front registering devices 20 and the pressure means 78 of the side registering means are determined by the cam 40. This cam has a concentric dwell 90 portion 94 which turns in contact with the roll 41^a of the lever 41 during the time when the side registering slide is in operation under the control of the cam 67. When the slide stops a low drop 95 on the periphery of the cam 40 comes opposite the roll 41^a, permitting the rock-shaft 38 to turn backward slightly. This movement is sufficient to lift the pressure member 78 of the side registering means off the paper, but 95 not sufficient to bring the front registering devices down upon the same. A further dwell of the rock-shaft-operated parts now ensues, corresponding to the portion 96 of the cam 40, and during this brief interval 100 the grippers of the gripper cylinder 17 seize the forward edge of the sheet and draw it off the feed surface and out of the field of action of the registering devices. Thereupon a rapid drop 97 upon the cam 40 passes 105 beneath the roller 41^a, and in response thereto the front registering devices are quickly carried backward to the receiving position of Fig. 3 and the pressure member 78 of the side registering means is lifted still 110 higher. At or about the same time the cam roll of the lever 68 moves to the other of the dwell portions of the cam 67, so that the slide 65 is moved in the direction away 115 from the side stop, and then held stationary 120 until the front registering devices have completed their operation upon the succeeding sheet. The reversibility of the cam 67 enables the movement of the slide to be reversed with respect to the operation of its 125 pressure device 61, so that, for example, when the said device is down upon the sheet the slide moves to the right instead of the left, thus enabling the paper to be alined 130 against either a left or a right side stop.

What is claimed as new is:

1. In a sheet feeder, a stationary terminal feed surface, and means for receiving and advancing successive sheets against a front stop characterized by flexible longitudinally disposed and reciprocating forwarding blades operating in frictional face contact with the sheet on the feed surface. 5
2. In a sheet feeder, front registering means comprising a terminal feed surface, flexible longitudinally disposed spring blades pressed in face contact thereon, and mechanism for advancing and retracting the blades relatively to the feed surface. 10
- 15 3. In a sheet feeder, front registering means comprising a stationary terminal feed surface, reciprocatory supports thereover, flexible longitudinally disposed friction blades carried by said supports and pressed 20 in face contact with the feed surface, and mechanism for reciprocating the supports to advance and retract the blades. 25
4. In a sheet feeder, a stationary terminal feed surface, front registering devices having flexible reciprocatory friction blades pressed in face contact on the surface, and means for advancing the blades, raising the same, returning them and holding them in readiness for a new sheet. 30
- 35 5. In a sheet feeder, a stationary terminal feed surface, a rocking support thereover, front registering devices carried by said support having forwardly projecting flexible friction blades pressed against the surface, and a cam for operating the rocking support. 40
6. A front registering device for sheet feeders comprising a reciprocatory member, a flexible friction blade projecting forward therefrom, and means for pressing the blade with its face against the paper. 45
7. In a sheet feeder, front registering means comprising a paper support, a flexible forwarding blade, means for advancing the blade in frictional face contact with the paper, and pressure means beneath which the blade travels. 50
8. In a sheet feeder, front registering means comprising a paper support, a flexible forwarding blade operative thereover, and a pressure roller bearing upon the blade. 55
9. In a sheet feeder, front registering means comprising a paper support, a flexible forwarding blade operative thereover, a pressure roller bearing upon the blade, and means for advancing and retracting the blade and for raising the same and the roller in the forward position. 60
10. In a sheet feeder, front registering means comprising a feed surface, a roller therein, a flexible forwarding blade operative over the feed surface and roller, and a pressure roller bearing upon the blade over the other roller. 65
11. In a sheet feeder, front registering means comprising a feed surface, a flexible forwarding blade, means for supporting the blade so as to present a tapering throat at the rear between it and the feed surface, means for pressing the blade in frictional face contact with the paper, and means for closing the throat and advancing and retracting the blade. 70
12. In a sheet feeder, front registering means comprising a terminal feed surface, a flexible spring blade lying thereon, a carrier from which the blade projects forward, said carrier being constructed to hold the rear portion of the blade off the surface so as to provide a tapering throat to receive the paper, and means for closing the throat and advancing and retracting the blade. 75
13. In a sheet feeder, the combination with a terminal paper support, of a front registering device comprising a spring blade, a pressure member bearing the blade against the paper support at a forward point, a carrier constructed to hold the rear end of the blade off the support in the receiving position, and mechanism for actuating the carrier to advance and retract the blade. 80
14. In a sheet feeder, the combination with a terminal paper support, of a front registering device comprising a flexible blade, a carrier for the rear end of the blade, said carrier being mounted so as to hold said rear end off the support in the receiving position, a pressure member bearing the blade against the support at a forward point, means for operating the carrier to advance the blade beneath the pressure device, and means for thereupon lifting the pressure member. 85
15. In a sheet feeder, the combination with a terminal paper support, of a front registering device comprising a flexible blade, a pressure member bearing the blade against the support at a forward point, and mechanism for advancing the blade beneath the pressure member and thereafter lifting the blade and member. 90
16. In a sheet feeder, the combination with a terminal paper support, of a front registering device comprising a flexible blade, a pressure member bearing the blade against the support at a forward point, means for holding the rear end of the blade off the support so as to provide a tapering throat to receive the paper and for thereupon closing the throat and advancing the blade beneath the pressure member. 95
17. In a sheet feeder, the combination with a terminal paper support, of a front registering device comprising a flexible blade, a reciprocatory carrier for the blade comprising a downward extending swinging arm and a forward projecting holder pivotally jointed on the arm and holding the rear end of the blade, and means forward of the carrier for pressing the blade against the paper support. 100
- 120
- 125
- 130

18. In a sheet feeder, the combination with a terminal paper support, of a front registering device comprising a flexible blade, a reciprocatory pivotally jointed carrier for the rear end of the blade, and means forward of the carrier for pressing the blade against the paper support.
19. In a sheet feeder, the combination with a terminal paper support, of a front registering device comprising a flexible blade, means resting upon the blade at a forward point to press the same against the paper support, and a carrier for the rear end of the blade comprising a reciprocatory member, a blade holder pivoted thereon, and means for limiting the movement of the blade holder on the member.
20. In a sheet feeder, the combination with a terminal paper support, of front registering means comprising a reciprocatory member, a forwardly projecting blade holder adjacent the paper support pivoted to the reciprocatory member, means limiting the pivotal movement of the holder on the member, a flexible blade projecting forward from the holder along the support to act upon the paper by frictional face contact, and means forward of the holder for pressing the blade upon the support.
21. In a sheet feeder, the combination with a terminal paper support, of front registering means comprising a transverse shaft, downward projecting rock-arms thereon, blade-holders pivoted to the lower portions of said arms and projecting forwardly, adjustment stops limiting the pivotal movement of the blade-holders on the arms, flexible blades extending forward from the blade-holders with their faces against the paper support, and pressure rollers resting on the blades.
22. A front registering device for sheet feeders, comprising, in combination with a terminal paper support, a flexible blade having its face against the paper support, means to which the rear end of the blade is secured for reciprocating the same, a forwardly located pressure device bearing upon the blade, and means whereby the blade-reciprocating means lifts the pressure device at the forward part of its stroke.
23. A front registering device for sheet feeders, comprising, in combination with a terminal paper support, a rocker supported upon a transverse axis and extending into proximity to said paper support, a flexible blade secured at its rear end to said rocker and having its face against the paper support, and a pivoted pressure device resting upon the blade, said rocker and pressure device being so constructed and arranged that the former raises the latter toward the conclusion of its forward stroke.
24. In a sheet feeder, the combination with a terminal paper support, of a transverse

rock-shaft, rockers fixed thereto and extending into proximity to the paper support, flexible blades secured at their rear ends to the rockers and extending forward with their faces against the support, and pressure arms loosely supported by the rock-shaft and extending in front of the rockers so as to rest upon the blades and to be lifted by the rockers toward the conclusion of the forward stroke.

25. A front registering device for sheet feeders, comprising, in combination with a terminal paper support, a flexible blade extending longitudinally with its face thereon, a pivotally supported pressure device resting upon the blade, a rocker to which the rear end of the blade is connected, and means for swinging the rocker so as to advance the blade beneath the pressure device and then to raise the pressure device and blade off the paper.

26. A front registering device for sheet feeders, comprising, in combination with a terminal paper support, a downward extending arm mounted to rock on a transverse axis, a forward projecting blade-holder pivoted to said arm and having a tail extending upward behind the same, adjustable stops limiting the pivotal movement of the blade-holder on the arm, one of said stops coöoperating with the tail, a flexible blade projecting forward from the blade-holder in face contact with the paper support, and pressure means bearing upon the blade.

27. In a sheet feeder, the combination of a side registering member beneath the forward portion of the path of the sheets, a transverse rock-shaft thereover, a front registering device operated by said rock-shaft, and a pressure device to coöperate with the side registering member also operated by the rock-shaft.

28. In a sheet feeder, the combination of a side registering member beneath the forward portion of the path of the sheets, a pressure device coöperative therewith, front registering devices, and mechanism for operating the front registering devices and raising them from the sheet, thereupon bringing such pressure device down upon the sheet over the side registering device, and then raising the pressure device while the front registering devices are still off the sheet.

29. In a sheet feeder, the combination of a side registering member beneath the forward portion of the path of the sheets, an operating rock-shaft thereover, front registering devices connected with the rock-shaft, and a pressure device also connected therewith for coöperation with the side registering member, said pressure device and front registering devices being connected in such relation that the pressure device descends while the front registering devices are oper-

ating forwardly and comes in contact with the sheet when the front registering devices have completed their forward movement and are raised by the rock-shaft.

- 5 30. In a sheet feeder, the combination of a side registering member beneath the forward portion of the path of the sheets, an operating rock-shaft thereover, front registering devices connected with the rock-shaft, 10 a pressure device also connected therewith for coöperation with the side registering member, said pressure device and front registering devices being connected in such relation that the pressure device descends 15 while the front registering devices are operating forwardly and comes in contact with the sheet when the front registering devices

have completed their forward movement and are raised by the rock-shaft, and means for operating the rock-shaft providing for 20 two dwells, one at the conclusion of the forward movement of the front registering devices while said pressure device is in contact with the sheet and the front registering devices are raised forwardly to free the sheet, 25 and the other following a short return movement of the rock-shaft which lifts the pressure device without causing the front registering devices to bear upon the sheet.

Dated, New York, June 30th, 1917.

OTTO KIRSCH.
